UNITED STATES PATENT OFFICE.

EBER ROBINSON, OF GREENVILLE, SOUTH CAROLINA, ASSIGNOR TO SHAMBOW SHUTTER COMPANY, OF WOONSOCKET, RHODE ISLAND, A CORPORATION OF RHODE ISLAND.

SPOOL.

Application filed August 19, 1924. Serial No. 732,953.

To all whom it may concern:

Be it known that I, EBER ROBINSON, a subject of the King of Great Britain, residing at Greenville, in the county of Greenville and State of South Carolina, have invented certain new and useful Improvements in Spools; and I do hereby declare the following to be a full, clear, and exact description of the invention, such as will enable others skilled in the art to which it appertains to make and use the same.

The present invention relates to spools or bobbins.

In spools or bobbins as ordinarily constructed the head is liable to become loosened on the barrel by reason of the blows which the spool or bobbin receives in being tossed into baskets or trucks, and in time the turning of the head on the spool weakens the means by which the head is held on the barrel so that the spool rapidly deteriorates and finally falls to pieces. The object of the present invention is to produce a construction of spool or bobbin by virtue of which, in addition to the ordinary means for holding the head on the barrel, means are provided for preventing the head from rotating with relation to the barrel, and also to produce a new construction of spool. To these ends the present invention consists in the spool or bobbin hereinafter described and particularly defined in the claims.

In the accompanying drawings illustrating the preferred form of the invention, Fig. 1 is an elevation, a portion of which is shown in section; and Fig. 2 is a cross-section on the line 2-2, Fig. 1.

The spool comprises a cylindrical barrel 10. The barrel end is round and is provided with a central extension 11. The end of the barrel is provided with a conical depression 12 which extends from the edge of the extension 11 into it to the bore of the barrel. The barrel head 13 is provided with a recess 14 on its inner side, which is round and receives the barrel end. This recess fits the barrel end. The head is also provided with a conical hole 15 to receive the barrel end extension 11. A bushing 16 having a conical head 17 fits the conical depression in the barrel end extension and overlaps slightly beyond such extension or takes against the outer portion of the conical hole in the barrel head which constitutes in ef-

fect a shoulder. Between the barrel end and the bottom of the recess 14 are steel balls 18. Two are sufficient in number for the purpose, and each ball is received in cavities in both the barrel end and head. These cavities are formed by vulcanizing the head on to the barrel with sufficient pressure to cause the balls to form the cavities in the head and barrel which receive them.

The spool is assembled by forcing the head on the barrel with two steel balls between, glue being applied to the contacting surfaces, then the bushing 16 is forced in to the end of the barrel, glue being applied to it, and sufficient pressure being exerted upon the parts to cause the parts to be accurately positioned with relation to each other, after which they are held in place by pressure if necessary until the glue is set.

The barrel end extension 11 as ordinarily formed is cylindrical on its peripheral surface, but the hole in the head is slightly tapered, as shown, with the result that when the bushing is forced into position with relation to the barrel and head, it presses the end of the barrel extension outwardly, or mushrooms it slightly, so as to cause the extension to interlock with the head, thereby contributing to securely unite the head and barrel together, although, of course, the bushing is the principal means for securing the head to the barrel to prevent longitudinal movement of the head on the barrel. The balls constitute locking members for holding the barrel and head from relative rotation.

The barrel may be made of wood, and the head of vulcanized fibre or other material harder than wood, if desired, and where the densities of the head and barrel are different, the ball embeds itself the more deeply in the element of lesser density. Thus, where the barrel is of wood and the head of vulcanized fibre, the ball will be more deeply embedded in the barrel than in the head, but it will embed itself in both and form cavities in both so as thereby to prevent rotation of the head on the barrel. In the drawings the balls 18 are shown as two in number, located on opposite sides of the barrel. These balls are inexpensive, and being small in size they embed themselves readily in the head and barrel under

the pressure ordinarily used in assembling spools. They are efficient in operation, and prevent any rotation of the head with respect to the barrel. The bushing is ordinarily made of wood, although other material may be employed if desired.

One of the difficulties which has heretofore been experienced in the use of vulcanized fibre for spool or bobbin heads has been that while the glue is efficient to unite wood to wood, it does not as efficiently unite wood to vulcanized fibre, as there is little penetration of the glue into the fibre, in consequence of which the present invention is particularly useful where the head is of hard material like vulcanized fibre, to which the glue does not adhere as readily as to wood. This enables the spool or bobbin to be made with durable heads, securely fastened on the barrel, so as to be held from rotational movement with relation thereto and consequent loosening of the head on the barrel, and at the same time the head is held firmly and securely in place from longitudinal movement by the bushing.

Having thus described the invention, what is claimed is:

1. A spool or bobbin having a barrel provided with a round end and an extension beyond the barrel end, a head provided with a round recess on its inner side to receive the barrel end and a hole to receive the barrel end extension, a ball for holding the barrel and head from relative rotation, the barrel end and the bottom of the round recess of the head being provided with opposed cavities extending the one into the barrel end and the other into but not through the head in which the ball is received, and means for engaging the barrel end extension and head to hold the head on the barrel.

2. A spool or bobbin having a barrel provided with a round end, a head provided with a round recess on its inner side to receive the barrel end, a ball for holding the barrel and head from relative rotation, the head and barrel being provided with longitudinally opposed cavities in which the ball is received, and a bushing for holding the head on the barrel.

3. A spool or bobbin having a barrel provided with a round end and an extension beyond the barrel end having a conical recess, a head provided with a round recess to receive the barrel end and having a conical recess to receive the barrel end extension, a bushing received in the barrel having a head occupying the conical recess in the end of the barrel extension and a shoulder extending beyond the barrel end extension engaging the conical recess in the head, and a small independent locking member extending into cavities in both the barrel and head for holding them from relative rotation.

4. A spool or bobbin having a barrel provided with a round end, an extension beyond the end having a conical recess in it, a head provided with a round recess on its inner side to receive the barrel end, and a conical recess to receive the extension, a bushing having a conical head received in the conical recess in the barrel extension and having a portion projecting beyond to engage the outer portion of the conical recess in the head for holding the head from longitudinal movement on the barrel, and a ball received in cavities in the contacting surfaces of the barrel end and the head for holding the head and barrel from relative rotation.

In testimony whereof I have signed my name to this specification.

EBER ROBINSON.
